Des. 211,348
Patented June 11, 1968

211,348

STORAGE BATTERY

John T. Redmon, Detroit, Mich., assignor to Globe-Union
Inc., Milwaukee, Wis., a corporation of Delaware

Filed Sept. 20, 1965, Ser. No. 87,067

Term of patent 14 years

(Cl. D26—6)

Fig. 2

Fig. 3

FIG. 1 is a perspective view of a storage battery showing one form of my new design wherein the top has recessed filler closures and a recessed panel with legends therein;

FIG. 2 is a front elevational view of the form shown in FIG. 1;

FIG. 3 is a left side elevational view of the form shown in FIG. 1;

FIG. 4 is a right side elevational view of the form shown in FIG. 1;

FIG. 5 is a rear elevational view of the form shown in FIG. 1;

FIG. 6 is a perspective view of a storage battery showing a second form of my new design wherein the top has flush filler closures; and

FIG. 7 is a top plan view of the form shown in FIG. 6. The bottom of the storage batteries shown in FIGS. 1-7 are plain and unornamented.

The characteristic features of my new design are shown in solid lines and reside in the combination with a substantially rectangular casing of vertical recesses of rectangular cross section at each end of the front and back surfaces, electrical conductor terminal fittings in the recessed ends of the front surfaces, centrally disposed vertical slots in each end of the battery, and a top surface provided with filler closures, all as shown and described.

I claim:

The ornamental design for a storage battery, substantially as shown and described.
